UNITED STATES PATENT OFFICE,

FREDERIC P. GATES, OF HARTFORD, CONNECTICUT, ASSIGNOR TO THE ARROW ELECTRIC COMPANY, OF HARTFORD, CONNECTICUT, A CORPORATION OF CONNECTICUT.

SWITCH-HANDLE.

1,166,345.

Specification of Letters Patent. Patented Dec. 28, 1915.

Application filed May 24, 1915. Serial No. 30,164.

To all whom it may concern:

Be it known that I, FREDERIC P. GATES, a citizen of the United States of America, and residing at Hartford, in the county of 5 Hartford and State of Connecticut, have invented a certain new and useful Improvement in Switch-Handles, of which the following is a specification.

My invention relates to switch handles 10 and particularly to handles for rotary snap switches, the object of my invention being to provide a suitable connection between the switch spindle and the handle, especially adapted for porcelain or like materials in 15 which it is difficult or impossible to mold a frame element such as is commonly used in the manufacture of composition or rubber handles.

In the accompanying drawings, Figure 1 20 is a vertical section through a switch handle in which my invention is embodied in one form; Fig. 2 is an inverted plan thereof showing the switch spindle partially in section; Fig. 3 is a vertical section on the 25 line 3—3, Fig. 1; Fig. 4 is a side elevation of a switch of a type in which a handle of the present character may be employed; Figs. 5 and 6 are perspectives of details; Fig. 7 is a vertical section of a modified 30 construction; Fig. 8 is a transverse section on the line 8—8, Fig. 7; Fig. 9 is a bottom plan of the same; Fig. 10 is a vertical section through a switch handle showing a further and modified embodiment of my 35 invention; and Fig. 11 is an inverted plan thereof.

In the embodiment of my invention illustrated in Figs. 1 to 6 inclusive, the handle 10 of insulation is provided with an axial 40 well 11 opening to the lower face of the handle. The inner portion of the well is of non-circular or polygonal contour and receives the correspondingly shaped head 12 of the ferrule 13 which is tapped at its 45 lower end 14 to afford a threaded connection with the switch spindle 15 of the ordinary snap switch.

Communicating with the well 11 near the 50 lower face of the handle is formed a bayonet slot recess, the entry channel 16 of which extends to the lower face of the handle, while the angled section 17 thereof forms an internal ledge 18 spaced from the lower 55 face of the handle. A locking plate 19 entering the outer portion 20 of the well is

provided with wings 21 which, during the insertion of the locking plate, pass through the entry channels 16 of the bayonet slot recess. After the locking plate has been inserted to a depth of the angle 17 of the 60 bayonet slot it is rotated to bring the wings 21 over the ledge 18. This locking plate forms a seat for one end of the spring 22 coiled on the ferrule beneath the head 12 thereof. It is thus obvious that after the 65 locking plate has been inserted and rotated into position to rest against the ledge 18, the ferrule 13 is securely engaged within the switch handle but with a lost motion connection which is normally taken up 70 by the spring 22. In order to prevent the reverse rotation of the locking plate which would bring the wings 21 into register with the entering channels 16 of the bayonet slot, lugs 23 are provided at the margins of the locking plate in such position 75 that when the wings 21 are fully seated against the shoulders 18, the lugs 23 may be pressed outward and into engagement with the side of the entry channel 16. In 80 this position they bear against one side of the entry channel 16 and prevent the reverse rotation of the locking plate. In this position of the lugs 23 it is impossible for the locking plate to be turned to a position in 85 which it might escape the ledge 18. A finish or cover plate 24 may be provided lying beneath the lower face of the handle and held in position by a spring washer 25.

In the modification shown in Figs. 7 to 90 9 the well 110 in the handle is cylindrical throughout the major portion of its depth, but has a rectangular pocket 111 of less diameter at its inner end to receive the head 95 26 of the correspondingly shaped ferrule 27. A split bearing washer 29, engaging the ferrule at the reduced neck 28, forms an abutment for one end of the spring 30, the other end of which rests against the locking plate 190. In this modification, the 100 locking plate is pierced by a rectangular aperture 119 which fits over the rectangular body 27 of the ferrule, and prevents rotation of these parts with relation to each other while at the same time permitting 105 the ferrule to pass through the plate. The locking plate is provided with the wings 21 as before and the bayonet slot 16—17 in the handle forms a supporting ledge 18 for these wings.

In order to assemble the handle and ferrule, the bearing washer 29, spring 30 and locking plate 190 are mounted on the ferrule 27 and the locking plate pushed down the ferrule toward the bearing washer 29 a sufficient distance to permit the wings 21 on the locking plate to enter the bayonet slot in the handle to the depth of the ledge 18 before the head 26 of the ferrule enters its rectangular pocket 111. In this position the ferrule is rotated to bring the locking plate wings 21 over the ledges 18, whereupon, the head 26 is permitted to enter its well 111 under the influence of spring 30. Inasmuch as the locking plate still engages the rectangular body of the ferrule and the head 26 of the latter now engages in the rectangular pocket 111 of the well, the parts are locked against relative rotary displacement, while at the same time permitting limited relative endwise displacement of the ferrule through the locking plate and against the action of the spring 30. The stem 140 of the ferrule is adapted for threaded engagement with the switch spindle, as before.

In the modification shown in Figs. 10 and 11, a construction embodying the same conception is illustrated. In this case the well 101 has a rectangular pocket 111 of reduced diameter at its inner end opening from the body of the well which is of generally cylindrical shape although provided with threads 36 molded into its inner periphery 35 and extending to the mouth of the well. The ferrule 32 is of rectangular shape and its head 31 is spaced from the body of the ferrule by a reduced neck portion 33 in which the bearing washer 34 is engaged. The spring 38 abuts at its inner end against this washer, while at its outer end it bears against the locking plate 37. The latter, in the present modification, is formed as an in-turned flange on the screw thimble 35, adapted to be threaded into the well on the internal helix 36 molded therein. A rectangular perforation 370 in the flange plate 37 engages the ferrule 32 and prevents relative rotation of the parts. Consequently in order to assemble the ferrule and handle, it is necessary, as in the modification just described, to draw the head 31 down within or toward the screw shell 35 while the latter (and the ferrule therewith) is being screwed into the well in the handle, whereupon the ferrule is released and the expanding spring 38 forces the head 31 into its rectangular pocket 111, thus holding the ferrule, handle and locking plate against relative rotary displacement.

The thimble 36 may be spun from sheet metal in the manner commonly employed in the formation of screw shells for lamp sockets, attachment plugs, etc. The switch spindle is attached in this instance by

screwing the end thereof into an internally threaded socket 114 in the ferrule.

Various further modifications of construction will readily suggest themselves which do not depart from what I claim as my invention.

I claim as my invention:—

1. A switch handle comprising a porcelain body recessed from its lower face to form a well, a switch spindle element engaged against relative rotary displacement in said well and means to prevent endwise separation of said parts, said means comprising a retaining member for the spindle element engaging an integral portion of the body of the handle and secured in said well by a rotary displacement of said member with relation to the handle.

2. A switch handle comprising an insulating body recessed from its lower face to form a well, a switch spindle element engaged against relative rotary displacement in said well, a bayonet-slot recess in the body of the handle and communicating with said well at the open end of the latter to form an offset ledge, in combination with a retaining member entering said well and having a portion adapted to enter said bayonet-slot recess and rest against said ledge on the rotation of said retaining member with relation to the handle.

3. A switch handle comprising an insulating body recessed from its lower face to form a well, a switch spindle element engaged against relative rotary displacement in said well, a bayonet-slot recess communicating with said well at the open end of the latter and forming an offset ledge, in combination with a retaining member entering said well and having a portion adapted to enter said bayonet-slot recess and rest against said ledge on the rotation of said retaining member with relation to the handle, together with a lug on said retaining member adapted to lock said retaining member in position on said ledge.

4. A switch handle comprising an insulating body recessed from its lower face to form a well, a switch spindle element engaged against relative rotary displacement in said well, and means to prevent endwise separation of said parts, said means comprising a retaining member for the spindle element secured in said well by a rotary displacement of said member with relation to the handle and a lug on said retaining member adapted to lock the same in said well.

5. A switch handle comprising an insulating body recessed from its lower face to form a well, a spindle element engaged against relative rotary displacement in said well, a bayonet-slot recess communicating with said well at the open end of the well to form an offset ledge in combination with a

retaining washer having a flange adapted to enter said bayonet slot and be rotated to position on said offset ledge, together with a lug on said washer engaging the side of 5 the bayonet slot in the assembled position of the parts to lock said washer against accidental escape from said recess

In testimony whereof I have signed my name to this specification, in the presence of two subscribing witnesses.

FREDERIC P. GATES.
